UNITED STATES PATENT OFFICE.

JOHN G. LUKENS, OF WHEELING, WEST VIRGINIA.

SIGHT-GLASS FOR WATER-COOLING SYSTEMS.

1,260,411.

Specification of Letters Patent. Patented Mar. 26, 1918.

Application filed October 21, 1916. Serial No. 126,938.

To all whom it may concern:

Be it known that I, JOHN G. LUKENS, a citizen of the United States of America, and resident of Wheeling, county of Ohio, and 5 State of West Virginia, have invented certain new and useful Improvements in Sight-Glasses for Water-Cooling Systems, of which the following is a specification.

This invention relates broadly to sight 10 glasses for water cooling systems, and more particularly to a sight glass for automobile radiators.

The primary object of the invention is to provide a device which permits a view of 15 the action of the water in automobile cooling systems of that character wherein an auxiliary tank or container for water is employed.

In such cooling systems as ordinarily employed, the lower end of the usual overflow pipe of the radiator is connected to a condensing coil located within a tank which is disposed at a convenient point on the automobile. Vapor due to heating of the water 25 escapes through the overflow pipe and passing through the coil is condensed. Also, as the water expands, due to heating, it rises in the radiator to a level where it overflows into the open end of the conductor pipe 30 leading to the condenser coil, whence it passes to and through said coil and is stored in the tank. On the other hand, when the water in the circulating system cools slightly 35 below that temperature which affords greatest motor efficiency, as when the throttle is closed, the water in the radiator recedes and a vacuum is created in the upper part of the latter, which acts to draw water from the tank through the coil and discharge it from the conductor pipe into the 40 radiator, refilling the latter.

As above indicated, the chief object of the present invention is to provide, in association with a cooling system of the general 45 character referred to, means whereby the action of the water as it overflows into the conductor pipe and as it returns through said pipe to the radiator, as aforesaid, may be exposed to view, permitting observation.

50 In describing the invention in detail, reference is herein had to the accompanying drawings, in which—

Figure 1 is a side elevation of the invention, and—

55 Fig. 2 is a central vertical section of the same.

Referring to said drawings, in which like

designating characters distinguish like parts throughout the several views—

1 indicates the usual filler tube provided 60 at the top of an automobile radiator. Ordinarily such tube is closed by a suitable threaded cap or cover, but the present invention contemplates the replacement of such cap or cover by a device embodying 65 a transparent sight glass, as 2. Said glass 2 is preferably of upright bulbous form having its lower end open and is rigidly seated upon or clamped to a hollow axially aligned metal member 3 having a neck portion 4 adapted for threaded engagement 70 with the filler tube 1. While the means of connecting the glass 2 to the member 3 may be varied, I prefer the means herein illustrated, the same involving in the formation 75 of the glass an annular horizontal base flange 5 and also the provision of a horizontal seat 6 in the member 3. Said base flange 5 is designed to seat upon the seat 6, a suitable gasket 7 being preferably interposed between said parts. Overlying said flange 5 is a second gasket 8 upon which rests an externally threaded clamping ring 9 which is adapted to be adjusted, as by a spanner wrench, for exerting clamping 80 pressure upon said flange, said ring being disposed in threaded relation with an upright annular flange 10 provided at the outer edge of the seat 6 of said metal member 3.

The conductor pipe 11 is so disposed in the radiator that it rises vertically within the bulb or glass 2 to a point which is substantially central with respect to the latter, as shown.

In practice, when the water in the radiator rises above the level of the upper end of the pipe 11, it overflows into the latter whence it is conducted through said pipe to the auxiliary water tank (not shown). 100 When the water within the radiator cools, it recedes from the bulb 2, producing a vacuum which acts to return water from said tank to the radiator, such water being discharged from the upper end of said pipe 105 11 in a jet or in the manner of a fountain. As is obvious, the arrangement of the upper end of the pipe within the glass bulb provides for visual observation of the movement or action of the water as it passes from 110 and returns to the radiator.

What is claimed is—

The combination with the filler tube of an automobile radiator, of a pipe projected

upward through said tube to a point above the top of the latter and having its upper end open, said pipe serving alternately as an overflow pipe and as a vacuum-induced 5 filler pipe for the radiator, and a glass cap mounted upon said tube in inclosing relation to said pipe and exposing to view the action of the water in entering and discharging from said open end, said cap being 10 wholly open at its lower end to permit un-

obstructed access of water thereto from the interior of the radiator.

In testimony whereof, I affix my signature in presence of two subscribing witnesses.

JOHN G. LUKENS.
